John W. Sharley
ATTORNEY

UNITED STATES PATENT OFFICE.

CHARLES WEIS, OF BALTIMORE, MARYLAND.

POCKET-BOOK PROTECTOR.

1,279,623.

Specification of Letters Patent. Patented Sept. 24, 1918.

Application filed February 28, 1918. Serial No. 219,629.

To all whom it may concern:

Be it known that I, CHARLES WEIS, a citizen of the United States, residing at Baltimore, in the State of Maryland, have invented certain new and useful Improvements in Pocket-Book Protectors; and I do hereby declare the following to be a full, clear, and exact description of the invention, such as will enable others skilled in the art to which it appertains to make and use the same.

My invention relates to pocket book protectors.

One object of my invention is to provide a simple, cheap and efficient means for securing a pocketbook within the pocket of a garment.

A further object of my invention is to provide a protector so constructed that the pocketbook may be readily secured within the pocket of the garment and readily removed therefrom.

A further object of my invention is to provide a pocketbook and a protector therefor so arranged that the two articles can be sold together, the former being capable of ready attachment within the pocket of a garment by means of an ordinary needle and thread.

A further object of my invention is to provide a protector of such a type that any number of said protectors can be attached within the pockets of various garments and be used for securing thereon either the same or different pocketbooks made according to my invention.

In the drawings:—

Figure 1 is a perspective view of a portion of the fabric constituting a pocket and having my improved protector secured thereto.

Fig. 2 is a perspective view of a pocketbook arranged for use with my improved protector.

Fig. 3 is an enlarged central section of the fastening member of my improved protector and a central section of a coöperating fastening member that is attached to the pocketbook.

Fig. 4 is a view of a pocket showing the pocketbook and protector in place therein.

In the drawings:—

10 is the fabric constituting a pocket of a garment.

11 is a strip of leather or woven fabric

which is secured to the fabric of the pocket 55 10 by means of stitches such as 12—12.

When the strip 11 is secured to the fabric 10, a slight looseness, shown by the space 13, may be provided between said strip and fabric for a purpose hereinafter explained.

A metallic washer 14 is placed on the outer side of the strip 11 and a similar washer 15 is placed on the inside thereof. The fastening member is the resilient ball 16 which is preferably formed of spring sheet 65 metal and is cut away so as to leave four spring zones, three of which are shown as at 17—17—17. The spring zones 17 are formed integrally with the collar portion 18 and the latter passes through holes provided in the 70 metallic washer 14, the strip 11 and the metallic washer 15 and the end of said collar portion is riveted over the washer 15 as at 19, and thus the fastening member is secured to the strip 11.

The coöperating fastening member which is attached to the pocketbook 20 comprises the following parts:—The washer 21 is formed integrally with the tapered sleeve 22 and the latter projects through a hole provided in the back 23 of the pocketbook 20. The sleeve 22 is flared outwardly as at 24 and between the flared portion 24 and the back 23 there is crimped the cap 25 which thus secures the coöperating fastening member to the back 23.

The mode of use and operation of my improved pocketbook protector is as follows:—

The strip 11 having been sewed to the fabric 10 within the pocket of a garment, the 90 wearer places the pocketbook 20 within the garment, then introduces either his thumb or forefinger within the space 13 and presses the sleeve 22 over the spring zones 17. Owing to the tapered shape of the sleeve 22, the 95 spring zones 17 will then secure the pocketbook in place.

When it is desired to remove the pocketbook 20 from the pocket of the garment, the wearer places two of his fingers between the 100 strip 11 and the back 23 of the pocketbook 20 and pushes the latter outwardly, thus removing the sleeve 22 from the spring zones 17, and then the pocketbook 20 can readily be removed from the pocket.

It will be noted that any number of strips with a fastening member attached thereto may be provided with each pocketbook and

said strips may be sewed in as many pockets as desired.

It will also be noted that any number of pocketbooks may be used with the same 5 strip 11.

It will further be noted that pocketbooks such as 20 may be sent from the factory with the coöperating fastening members secured thereto and with the zones 17 in the sleeves 10 22 thereof, thus securing the strip 11 to the pocketbook during shipment and sale.

I claim:—

1. In a pocketbook protector, the combi-

nation with a pocket and pocketbook, of a strip sewed only at its ends to said pocket, 15 a fastening member secured to said strip and a coöperating fastening member secured to said pocketbook.

2. In a pocketbook protector, the combination with a pocket and pocketbook, of a 20 strip sewed only at its ends to said pocket, a resilient fastening member secured to said strip and a rigid coöperating fastening member secured to said pocketbook.

In testimony whereof I affix my signature. 25
CHARLES WEIS.
